UNITED STATES PATENT OFFICE.

ARTHUR NEAL FUNK, OF FORT WORTH, TEXAS.

ADVERTISING ATTACHMENT FOR SCALES.

1,346,488.

Specification of Letters Patent.

Patented July 13, 1920.

Application filed July 24, 1919. Serial No. 313,000.

To all whom it may concern:

Be it known that I, ARTHUR NEAL FUNK, a citizen of the United States, and a resident of Fort Worth, county of Tarrant, and the State of Texas, have invented new and useful Improvements in Advertising Attachments for Scales, of which the following is a specification.

My invention is an improvement in advertising attachments for scales, and has for its object to provide an attachment of the character specified, wherein a series of display members are provided, mounted to be moved into different positions, to bring different matter into display position, and controlled to movement by the stepping onto the weighing platform of the one to be weighed.

In the drawings:

Figure 1 is a vertical section;

Fig. 2 is a vertical section at right angles to Fig. 1;

Fig. 3 is a detail of the locking device, with parts in section;

Fig. 4 is a perspective view of one of the display members.

The present invention is especially adapted for use with weighing scales of the automatic type, and the invention is shown in connection with a scale of this character indicated at 1. The hollow standard 2 that extends up from one end of the platform, and communicates with the chamber 3 in the platform carries a casing 4 at its top.

This casing has a series of horizontally extending slots or openings 5 in the face adjacent to the platform, and behind these openings within the casing are arranged the display members. In the present instance, each of these members is a roller 6 of triangular cross section, having three faces, upon which advertising matter of any desired character may be placed.

Each roller has axial journal pins 7 at its ends, and these pins are journaled in the end walls of the casing, so that the rollers may be rotated to bring either face to the front, and the slots 5 are of a size to display almost the full area of a face.

The rollers are constrained to rotate together and in unison by means of a sprocket chain 8, which engages sprocket wheels 9 on the rollers at one end. Each roller has a sprocket wheel, and there are in the present instance four rollers.

A locking means is provided for holding the rollers with the display faces squarely

before the openings; the said means being spring controlled, and releasable but preventing accidental displacement of the rollers. It will be understood that the rollers are so connected by the chain that the display faces of the series of rollers will be always in the same plane.

This locking means comprises a cam wheel 65 or disk 10, secured to one of the rollers, in the present instance, the second from the bottom, and this wheel has depressions 11 in its periphery, corresponding in number and relative position to the number and relative 70 position of the display faces.

A locking wheel or roller 12 engages the periphery of the cam disk, the said roller being journaled between arms 13 on the end of a rod 14, which is mounted, to slide in a 75 casing or cylinder 15 secured to the rear wall of the casing 4.

The rod has a head 16 at its inner end, fitting the casing, and a coil spring 17 is arranged between the head and the bottom of 80 the casing, and acts normally to force the roller toward the cam disk. When the cam wheel is turned, the raised portions thereof will move the roller 12 away from the disk, but when the raised portion is past the locking wheel or roller will move into the succeeding depression to lock the parts.

The movement of the display rollers is controlled by an auxiliary platform 18 hinged at 19 in a rabbet in the upper surface 90 of the platform top. When the auxiliary platform is in lowered position, its upper face is flush with the upper face of the platform of the scale.

A lever 20 is pivoted within the chamber 95 3 intermediate the ends of the lever and to the top of the chamber, as indicated at 21, and the forward end of this lever has an upwardly extending angular portion 22, which passes through to an opening in the 100 top of the platform 4 and engages the under face of the auxiliary platform near its free end.

The rear end of the lever 20 is connected to the lower end of the lower section 23^a of 105 a rod consisting of the portion 23^a and a portion 23. This rod 23—23^a is mounted to slide vertically in the standard 2 and the portion 23 of the rod has a head 24 at its upper end.

The head 24 has a slot 25 extending transversely of the head, and a pin 26 on one end of a lever 27 engages within the slot. The lever is pivoted at 28 intermediate its ends,

and the end remote from the pin is connected by a link 29 with a pawl or pusher 30, which coöperates with a ratchet chain 31^a. This chain is supported by sprocket 5 wheels 32 and 33, on the lowermost roller 6, and on the wall of the casing 4, and it will be obvious that when the rod 23 is moved upward by the downward movement of the auxiliary platform, the pawl will be pushed downward and the rollers will be turned.

The arrangement is such that the swinging of the auxiliary platform into the rabbet of the platform 4 under the weight of 15 the user will advance the chain 31 far enough to move each roller 6 a sufficient distance to bring another display face into display position.

The rod 23 is normally pulled downward 20 by coil springs 30 which are arranged between the rod and the opposite side walls of the hollow standard. Should this rod 23 be connected directly to the lever 20 at all times, the fine adjustment of the scale might 25 be disturbed, and means is provided for releasing the connection when the change of the rollers 6 has been made.

The sections 23—23^a of the rod are normally out of alinement and so held by a 30 cross pin 31 in the standard which is engaged by a cam block 32 on the lower section 23^a. A coil spring 33 normally acts to draw the said lower section toward the pin.

When the section 23^a of the rod is moved 35 upward by the swinging of the lever 20, the engagement between the cam and the pin will cause the section to move rearwardly at its upper end and away from the adjacent end of the section 23. The ends are 40 always out of alinement, and the section 23^a engages an extension 34 on the section 23.

The operation of the device is as follows: When one steps upon the auxiliary platform, it is depressed until it rests upon the 45 weighing platform. The lever 20 is rocked, the section 23^a of the rod 23—23^a, is moved upward, and the end of it engages the nose or extension 34 of the section 23.

This section is also moved upward and 50 the chain 31 is moved to cause the lowermost display roller to turn far enough to display another face at the adjacent opening 5. Since the display rollers are constrained to turn together, each brings to 55 view a new face, and all are before the one being weighed.

The cross rod 31 acting on the cam 32 is gradually moving the section 23^a rearwardly, and at the moment when the auxiliary platform is fully depressed and the display rollers are in display position, the section 23^a is moved out of engagement with the section 23, that is, the connection between the auxiliary platform and the display rollers is broken.

The movement will attract the attention of the one on the scale, and he will notice the advertisements, whereas if there were no movement, he would probably give them no attention. The lock holds all of the rollers 70 in display position against any chance of accidental displacement.

I claim:

1. In combination with a platform scale, of an auxiliary platform hinged at one end 75 to the upper face of the scale platform; a series of similar display members of polygonal cross section, having display matter on their faces, and mounted to rotate on parallel axes, means for constraining them to 80 rotate together, and a connection between the auxiliary platform and one of the members for rotating said members through a predetermined arc when the auxiliary platform is depressed, said connection being re- 85 leasable, and means for releasing the same when the auxiliary platform is fully depressed.

2. In combination with a platform scale, of an auxiliary platform hinged to the scale 90 platform, a series of display rollers, journaled on parallel axes in the standard of the scale and carrying display matter, means for constraining the rollers to move together, means for normally holding the auxiliary platform lifted and depressible under the weight to be weighed, a connection between the said means and the rollers for moving said rollers through a predetermined arc when the auxiliary platform is 95 100 depressed, means for releasing said connection when the auxiliary platform is fully depressed, and releasable locking means for holding the rollers when the connection is released.

3. In combination with a platform scale, of an auxiliary platform hinged to the scale platform, a series of display rollers, journaled on parallel axes in the standard of the scale and carrying display matter, means 110 for constraining the rollers to move together, means for normally holding the auxiliary platform lifted and depressible under the weight to be weighed, a connection between the said means and the rollers for moving said rollers through a predetermined arc when the auxiliary platform is 115 depressed, means for releasing said connection when the auxiliary platform is fully depressed, and releasable locking means for holding the rollers when the connection is depressed.

4. In combination with a platform scale, of an auxiliary platform above the scale platform, a display roller, means controlled by the downward movement of the auxiliary platform for moving said display roller 125 through a predetermined arc, and means controlled by the depressing of the platform for releasing said controlling means.
